DESIGN FOR A TEXTILE FABRIC

Evangeline Guarine, New York, N. Y., assignor, by mesne assignments, to Semaria Bros., Inc.,
New York, N. Y., a corporation

Application November 15, 1937, Serial No. 72,867

Term of patent 3½ years

To all whom it may concern:

Be it known that Evangeline Guarine, a citizen of the United States and resident of New York city, in the county of Kings, State of New York, has invented a new, original, and ornamental Design for a Textile Fabric, of which the following is a specification, reference being had to the accompanying drawing, forming part thereof, and in which,

The single figure of the drawing illustrates textile fabric embodying my new design.

The design unit is contained between the dot and dash lines, which unit is repeated in regular succession as indicated by the extensions beyond the unit boundaries.

I claim:—

The ornamental design for a textile fabric substantially as shown and described.

EVANGELINE GUARINE.
